UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 13,260, dated August 22, 1882.

Application filed July 21, 1882. Term of patent 3½ years.

To all whom it may concern:

Be it known that I, DAVID G. MELVILLE, of Medford, in the county of Middlesex and State of Massachusetts, have invented a new and original Design for Carpets, of which the following is a specification.

The nature of my design is fully shown in the accompanying photographic illustration.

The design is composed of a ground ornamented by Grecian and other borders, rectangular figures placed diagonally, and octagonal figures partly overlapped by the diagonal rectangular figures, and floral and foliage ornamentation scattered over the ground ornamented as described. 15

I claim—

The design for a carpet, substantially as shown and described.

In testimony whereof I have signed my name to this specification, in the presence of two subscribing witnesses, this 18th day of July, 1882. 20

DAVID G. MELVILLE.
